UNITED STATES PATENT OFFICE.

JOHN PRESSLEY COLEMAN, OF SWISSVALE, PENNSYLVANIA, ASSIGNOR TO
THE UNION SWITCH AND SIGNAL COMPANY, OF SAME PLACE.

RAILWAY SIGNALING.

SPECIFICATION forming part of Letters Patent No. 548,426, dated October 22, 1895.

Application filed May 28, 1895. Serial No. 550,971. (No model.)

To all whom it may concern:

Be it known that I, JOHN PRESSLEY COLEMAN, a citizen of the United States, residing at Swissvale, in the county of Allegheny and State of Pennsylvania, have invented or discovered certain new and useful Improvements 5 in Railway Signaling, of which improvements the following is a specification.

The invention described herein relates to 10 certain improvements in signaling double tracks and in interlocking the signal-operating mechanisms of adjacent towers or towers at the opposite ends of a block-section, whereby the tracks of such block-section may be 15 used for traffic in both directions, regardless of the normal direction of traffic on each of said tracks.

In general terms the invention consists in 20 the arrangement of two signals at each end of a block-section, both signals at one end being adapted to control traffic or train movements in the same direction, one on one track and the other on the other track, while both signals at the opposite end control movements 25 of trains toward the first-mentioned signals, one on one track and the other on the other track, the signal-operating mechanisms at each end of the block-section being so interlocked by suitable devices that when the signal 30 for one track at one end of the block-section is "clear" the signal for the same track at the opposite end of the block-section is locked at "normal" or "danger," and the invention further consists in the arrangement 35 of suitable devices along the tracks operated by train movements and adapted to prevent, when the train is in the block, the clearing of a signal for an opposite train movement on the track occupied by said train.

40 In the accompanying drawings, forming part of this specification, Figures 1, 1^a, and 1^b illustrate in plan a block-section having my improvements applied thereto, said several figures forming parts of a general diagrammatic view of the block; and Fig. 2 is a diagrammatic view illustrating a signal slot-circuit employed in the general plan.

45 As will be readily understood by those skilled in the art, the invention hereinafter described can be practiced by employing either of the three well-known systems of sig-

naling—*i. e.*, mechanical, electric, or pneumatic—or by a combination of any two or all of said systems, and although for convenience and clearness of illustration and description 55 the embodiment set forth herein is confined to one of said systems the invention is not to be limited to such system.

The signals for the normal operation of the tracks are on the west-bound track distant signal C, primary signal B, and automatic signal D. The signals for the east-bound track are the distant signal W, primary or home signal R, and automatic signal J. The signals for the reverse operation of the west-bound track 65 are primary signal S and automatic signal H, and for the reverse operation of the east-bound track the primary signal A and automatic signal L are used.

The circuits for the distant signal C are 70 formed by the battery 1, one pole of which is grounded or connected to ground-wire x, wire 2, armature 3 of relay 4, wire 5, make-and-break mechanism a, wire 6, armature 7 of track-relay 8, slot 9 of signal C, and wire 10 to 75 ground. The completion of this circuit of the distant signal, in order to hold its slot in normal position, is dependent upon the completion of the circuit of relay 4 and also of the closing of make-and-break mechanism a. The 80 circuit of relay 4 starts from battery 11 at tower I I, one pole of the battery being attached to the ground-wire x and is formed by armature 12 of relay 13, wire 14, make-and-break mechanism 15, which is closed only 85 when reverse-signal H⁴ is at "danger," wire 16, signal-operating mechanism of normal signal D, wire 17, relay 4, wire 18, contact-plate 19, lever 20, contact-plate 21, and wire 22 to ground. Thus it will be seen that not only 90 must the lever 20 be in normal position to connect contact-plates 19 and 21, but the west-bound track must be clear up to the point y at tower I I, as the armature 12 is against its contact-point, so as to complete the above-described circuit only when the circuit of the relay 13 is completed, said circuit being dependent upon or formed in part by the armatures 35 and 38 of track-relays 36 and 39 in sections 4 and 5.

100 The make-and-break mechanism a is only completed when the primary signal B is at

"safety." This signal has its operating-lever electrically locked, the lock being controlled by magnet 23. The circuit of this magnet is formed by battery 1, wires 2 and 24, relay 23, 5 wire 25, hand-actuated switch or make-and-break mechanism 26, wire 27, armature 28 of relay 29, wire 30, contact-plate 31, switch-lever 20, contact-plate 21, wire 22 to ground. It is apparent that the completion of the 10 circuits through magnet 23, whereby the signal-lever is unlocked, is dependent upon the normal position of the lever 20, and that the track from signal B to a distance beyond the signal D equal to the length of the overlap must 15 be clear, as the magnet 29 has its circuit formed in part by the armature of a track-relay 45, whose circuit is formed by an insulated track-section extending to signal D, and is also formed in part by the armature of a 20 relay 36, whose circuit is formed by the rails of the overlap section 4.

The signal B having been cleared by the operator of tower I, he is then free to clear signal C, permitting the train to advance 25 upon sub-section 1. The presence of the train upon this sub-section will short-circuit relay 8, thereby permitting the armature 7 to so move as to break the circuit through the slot 9, whereupon said signal will go to "danger." 30 As the train enters upon sub-section 2, its relay 32 will be short-circuited, thereby breaking the circuit through the slot 33 of signal B, permitting such signal to go to "danger." As the train enters upon sub-section 3, the circuit 35 of relay 29 will be broken through the short-circuiting of the relay 45 of such track-section, and the break in the circuit of said relay 29 will permit armature 28 to be so shifted as to break the circuit of the locking-magnet 40 23 of the lever of the signal B, thereby locking up such signal until such time as the train has passed off of sub-section 3 and overlap section 4.

As the train enters overlap section 4, its relay 36 will be short-circuited, thereby breaking the circuit of relay 13, whose circuit is formed by battery 34, connected at one pole to the ground-wire x , armature 35 of track-relay 36, wire 37, armature 38 of track-relay 39, 45 relay 13, and wire 40 to ground. The breaking of the circuit of relay 13 permits armature 12 of the circuit in which the operating mechanism of signal D is included to so shift as to break such circuit, thereby causing 50 the signal D to go to "danger." This signal is held at "danger" while the train passes over sub-section 5, as the presence of the train on said sub-section will short-circuit relay 39, thereby forming another break in the circuit 55 of relay 13, holding the same open, and through its medium holding the circuit of the signal D open at the armature 12. The passing of the train off of the overlap section 4 will restore the circuit, consisting of battery 60 41, having one pole connected to the ground-wire x , armature 42 of relay 36, wire 43, armature 44 of track-relay 45, relay 29, whose op-

posite pole is connected to ground-wire x . The closing of this circuit causes the armature 28 of relay 29 to so move as to close the 70 circuit through the locking-magnet 23, thereby permitting of a movement of the lever of signal B as to again clear such signal so that another train can pass on by tower I.

The lever 20 is controlled by a lock 46, operated by the armature of a magnet 47, said lock being so constructed that when the circuit of said magnet is open the lever is locked as against movement, but when the circuit of the magnet is closed the lever can be shifted. 80 The lock is further constructed so as to hold the lever in either of its positions. The function of this lever is, when in normal position, to permit the operation of the circuits hereinbefore described with the accompanying 85 movements of signals, but when shifted to reverse position will lock such signals in "danger" position by breaking the circuits necessary for their movement to "safety" position, and completes certain other circuits necessary 90 for the operation of signals for the reverse movement of trains. Hence it is necessary that such lever should be locked in its different positions while trains are passing along between towers I and II or while the signals 95 are set to permit such movements of trains. The circuit in which magnet 47 is included consists of wire 48, connected to ground x , magnet 47, wire 49, make-and-break mechanism 50, wire 51, armature 52 of relay 29, 100 wire 53, armature 54 of relay 13, wire 55, make-and-break mechanism 56, wire 57, battery 58 to ground x .

The make-and-break mechanism 50, which is of any suitable construction, is arranged 105 to be opened by the lever-operating signal B when shifted to set such signal to "safety," thereby opening the circuit through magnet 47 and locking the lever 20 in normal position. The break or opening of the circuit 110 through magnet 47 is continued by the train passing onto sub-section 3 through the short-circuiting of relay 45, the breaking of circuit 115 of relay 29, and the consequent movement of their armatures by the short-circuiting of relays 36 and 29 by the presence of a train on overlap section 4, and the short-circuiting of relay 39 and consequent demagnetization of 120 relay 13 by the presence of a train upon sub-section 5. Thus it will be perceived that 125 from the time the signal B is set to "safety" the circuit through magnet 47 is broken, with a consequent locking of lever 20 until the train passes beyond the point y .

The make-and-break mechanism 56 in the 130 circuit of magnet 47 at tower II is so arranged as to be opened by the lever-operating signal S, which controls the movement of trains from the last-bound to the west-bound track, so that when the operator in tower II has obtained permission, as hereinafter described, 135 to send trains in the reverse direction over the west-bound track, and has set his signal for such movement of the trains to the west-

bound track, the operator at tower I cannot shift his lever 20 and change the circuits of the several parts operated or controlled thereby.

The signals A, B, C, R, S, and W are provided each with a slot mechanism of any suitable well-known character or construction controlled by relays and track circuits in or adjacent to the ends of the blocks. The slot mechanisms of the distant signals C and W are controlled, as is customary, by the relay track-circuit and also by the make-and-break mechanisms *a*, which are operated by the normal primary signals B and R at the ends of the block. The slot mechanisms 77 and 77^a and 33 and 33^a, controlling the signals B, A, R, and S, are controlled by short track-sections numbered 2 and 7, and are also controlled by the sub-sections and overlapping sections between the two towers—that is to say, the slot 33 of signal B has its circuits controlled by sub-section 3 and overlap section 4. The circuit of the slot 33 of signal B consists of battery 78, one pole of which is connected to the contact-point of armature 79 of relay 32, armature 79, wire 80, slot 33, wire 81, switch 82, the movable member of which is connected to the rails of the crossover switch *m* or mechanism for operating the same and wire 83 to the other pole of the battery. The circuit of the slot 77 of signal A consists of battery 78, armature 79, wire 80, slot 77, wire 84, one pole of the switch 82, the movable member of said switch, and wire 83 to the battery.

It will be observed that each of the above circuits is formed in part by the armature 79 of the relay 32, so that it is necessary that said relay should be excited in order to permit of the operation of the signals A and B through their slots.

The circuit of sub-section 2 consists of battery 85, wire 86, one of the rails of said sub-section, wire 89, armature 90 of the relay 32, wire 91, relay 32, which has its opposite pole connected to the other rail of sub-section 2, said rail being connected to the opposite pole of battery 85. As the circuit just described is formed in part by the armature 90 and relay 32, it is obvious that some means must be employed in order to restore said circuit after it has once been opened by the passage of a train over sub-section 2. This is effected by employing an auxiliary circuit, which consists of battery 85, one rail of track-section 2, wire 89, wire 94, contact-point and armature 95 of locking-magnet 59^a, wire 96, contact-point and armature 97 of locking-magnet 23, wire 98, wire 91, relay 32, wire 92, rail of sub-section 2, wire 93, to battery. It will be observed that this last or auxiliary circuit passes through relay 32 and is formed in part by the rails of track-section 2, so that it as well as the main circuit of the relay 32 will be broken by the entrance of train upon sub-section 2; but as this auxiliary circuit does not pass through the armature 90 of relay 32 such circuit will be restored by the passage

of the train off of sub-section 2, thereby exciting magnet 32, so that its armature 90 will be attracted against its contact-point, restoring the main circuit of said relay. As the auxiliary circuit of relay 32 is formed in part by the armatures 95 and 97 of the magnets 59^a and 23, respectively, said armatures are so arranged as to complete the auxiliary circuit only when the magnets 23 and 59^a are broken and the armatures of said magnets in position to lock the levers of signals A and B at normal or "danger."

The operation of the slot-circuits of signal B is as follows, it being supposed that a train is approaching tower I in the normal direction of traffic on the west track: The operator closes the circuit through magnet 23 by pressing on the button of make-and-break mechanism 26, thereby unlocking the lever of signal B, which is then cleared. The clearing of this signal closes the circuit of slot of the distant signal C at *a*, thereby permitting the operator to pull signal C to "clear." As the train passes signal C and enters on sub-section 1, relay 8 is short-circuited, thereby permitting such a movement of its armature as will break the circuit of slot 9, whereupon the distant signal will go to "danger." The closing of the circuit of magnet 23 so shifts its armature 97 as to unlock the lever of signal B, as before stated, and also to break the auxiliary circuit of relay 32, and the movement of this lever to shift signal B to "safety" will hold the armature 97 away from its contact, as will be understood by reference to Fig. 2, until the lever is restored to normal position. The breaking of this auxiliary circuit will not effect relay 32, as its main circuit, consisting of battery 85, wire 86 of sub-section 2, wire 89, armature 90, wire 91, relay 32, wire 92, other rail of sub-section 2, wire 93, is closed. As the train enters on sub-section 2 the main circuit of relay 32 is shunted through the wheels of the train, thereby permitting the armatures 79 and 90 to move and break the circuit through slot 33 and also break the circuit of the relay. The break in the circuit of slot 33 permits signal B to go to "danger," and this movement of the signal forms at another break in the circuit in the slot 9 of the distant signal C, whose circuit would otherwise be closed by the movement of the train off of sub-section 1. The break in the main circuit of relay 32, caused by the movement of its armature 90, will not be restored by the movement of the train off of sub-section 2, as said armature forms a part of the circuit. The break in the main circuit of relay 32 can only be restored by a closing of its auxiliary circuit by the movement of armature 97 against its contact, and such movement can only occur when lever of signal B is returned to normal position, thereby permitting of the armature to lock the lever. After the armature has moved into position to lock the lever and close the auxiliary circuit of relay 32 it will remain in such position

until the circuit through magnet 23 is closed. This circuit cannot be closed until the train has passed off of sub-section 3 and overlap section 4, as the relay 29, whose armature 28 forms a part of the circuit of magnet 23, is controlled by track-relays 45 and 36 of sub-section 3 and overlap section 4, respectively, as hereinbefore stated. As signals A and B cannot be used simultaneously, the same battery 78 can be used for the slots of both signals, the battery being shifted from one slot-circuit to the other by the switch 82, which is controlled by the crossover switch or the mechanism for operating the same. As the distant signal C is not cleared for a reverse movement of trains over the west-bound tracks, the circuit for its slot 9 is not controlled by signal A. The east-bound track is provided with a similar system of signal-circuits, locking and track circuits, signals, and make-and-break mechanisms, as hereinbefore described, and said parts are designated by the same numerals as the corresponding parts hereinbefore described in connection with the operation of the west track, with the index-letter *a* attached. If, now, it be desired to send a train over the west-bound track in a reverse direction—*i.e.*, from tower II to tower I—the operator at tower II must ask permission from the operator at tower I for the reason that the magnet 59, which controls the lock of the lever for operating signal S, controlling the movement of trains from the east-bound to the west-bound track in the reverse direction, is included in a circuit whose battery is located at tower I and which is controlled by the switch 20 at said tower. The circuit of the magnet 59, commencing at tower I, consists of battery 60, one pole of which is connected to ground *a*, contact-strip 61, lever 20, when shifted, contact-strip 62, wire 63, armature 64 of relay 13, wire 65, manually-operated switch 66, magnet 59, and wire 67 to ground.

45 As hereinbefore stated, the lever 20 cannot be shifted from its normal or left-hand position to the reverse or right-hand position, until all the signals controlling the normal movements of trains on the west-bound track are at "danger" and such track between the towers I and II is entirely free from trains. By the shifting of the lever 20 the circuit for the normal signal D is broken thereby setting said signal to "danger" and the circuit through the magnet controlling the lever of signal B is also broken, thereby locking the lever and signal in normal or "danger" position, and as a consequence of the locking of signal B in a normal position the distant signal C is locked in the same position by the break in its slot-circuit at *a*. The shifting of this lever or switch 20 to reverse position closes the circuit, as hereinbefore stated, through the locking-magnet 59 of the lever-operating signal S, and also the circuit consisting of battery 60, contact-strip 61, lever 20, contact-strip 68, wire 69, armature 70 of relay 29, wire 71, make-and-

break mechanism 72, which is closed only when signal D is at "danger," wire 73, signal-operating mechanism 74 of reverse signal H, 70 wire 75, and ground *a*—that is to say, the movement of the lever or switch 20 to reverse position not only unlocks what might be termed the "starting signal" S for the reverse movement of trains along the west-bound 75 track, but supplies current for the operation of the reverse signal H, which controls the movements of the trains in a reverse direction along the west-bound track in the same manner that the signal D governs normal movement of trains along said track. The signal S having been set to "safety," the train passes by the signal over the crossover from the east to the west bound track. The movement of the train over the sub-section 7 short-circuits the relay 32^a, which controls the circuit of the slot mechanism 77^a of said signal, and thereby sets the signal to "danger" behind the train. The slot-circuit is held open by means of a break in the circuit through the magnet 59, said slot-circuit being formed in part by the armature of said magnet, as was described. The break in the circuit of magnet 59 is formed by the short-circuiting of relay 39 through the presence of a train on sub-section 5 and the short-circuiting of relay 39 permits such a shifting of its armature 38 as will break the circuit of relay 13 and thereby permit armature 64 to move away from its contact-point and break the circuit of magnet 59 at that point. The break in the circuit of magnet 59, whereby the slot-circuit is held open, is continued while the train passes over sub-section 5, and as a train enters upon overlap section 4 another break is formed by the short-circuiting of relay 36 and the consequent movement of the armature 35, which is included in the circuit of relay 13, controlling, as before stated, the circuit of magnet 59. After the train has passed off of the overlap section the circuit of magnet 59 is completed, and the signal S can be sent to "safety" to permit the passage of another train in a reverse direction over the west track. The entrance of the train upon overlap section 4 and the consequent short-circuiting of relay 36 breaks the circuit of relay 29, thereby permitting armature 28 to drop away from its contact-point and break the circuit of reverse signal H. The break in this signal-circuit is continued by the entrance of a train upon sub-section 3, which short-circuits relay 45, thereby forming another break in the circuit of relay 29, permitting the armature 28 to stay in an open position. Reverse signal H is held at "danger" until the train has passed off of sub-section 3 and entered into the control of the operator at tower I.

After the operator at the tower II has sent a train in a reverse direction over the west-bound track, he is at liberty, provided the train has passed the overlap section 4, to send another train over the same line or else in a normal direction over the east-bound track,

in which case its movements will be controlled by the signals W, R, and J, corresponding to the signals C, B, and D for the normal operation of the west-bound track.

5 If desired, both tracks may be reversely operated at the same time, the operators in both towers shifting their levers 20 and 20^a to reverse position. Thus it will be readily understood that by properly interlocking the signal-operating mechanism in the two towers the two tracks may without danger be operated as desired.

I claim herein as my invention—

1. A double track block section having in combination two signals at or near each end of the block, the signals at one end controlling the movement of trains in the same direction, one over one track and the other over the other track, mechanisms for operating said signals, the mechanism of the signal controlling train movements over one track at one end of the block being interlocked with the mechanism of the signal controlling train movements over the same track at the opposite end of the track, substantially as set forth.

2. A double track block section having in combination two signals at each end, one controlling the normal movement of trains over one track, and the other controlling the reverse movement of trains over the other track, and mechanisms for operating said signals, the mechanism for operating the normal signal at one end being interlocked with the mechanism for operating the reverse signal at the opposite end of the block, substantially as set forth.

3. A double track block section having in combination two signals at each end, one controlling the normal movement of trains over one track, and the other controlling the reverse movement of trains over the other track, mechanisms for operating said signals, the mechanism controlling the normal signal at one end being interlocked with the mechanism controlling the reverse signal at the opposite end of the block, and mechanism controlled by the movement of trains along the block section for preventing a change or reversal in the manner of operating a track of the block section, while in condition for the passage of a train along the same, substantially as set forth.

4. A double track block section having in combination two signals at each end, one controlling the normal movement of trains over one track, and the other controlling the reverse movement of trains over the other track, mechanisms for operating said signals, and

mechanism controlled by the movement of trains along the block section for preventing a change or reversal in the manner of operating a track of the block, while a train is passing along the same, substantially as set forth.

65

5. A double track block section having in combination two signals at each end, one controlling the normal movement of trains over one track, and the other controlling the reverse movement of trains over the other track, mechanisms for operating said signals, an electric lock for each of the signal operating mechanisms, the circuits for said locks extending from end to end of the block section, an electric switch in each of said circuits, the electric switch of the normal and reverse signal circuits for the same track being at the same end of the block section as the normal signal, substantially as set forth.

6. A double track block section divided into two sub-sections and an intervening overlap section, and having in combination two signals at or near each end of the block, the signals at one end controlling the movement of trains in the same direction, one over one track and the other over the other track, mechanisms for operating said signals, locks for controlling the signal operating mechanisms, and means operated by movements of trains over the sub-sections and overlapping sections, for controlling said locks, whereby a signal at the end of the block is held at "danger" behind a train, until the latter has passed off the overlap section, substantially as set forth.

95

7. A double track block section divided into two sub-sections, and an intervening overlap section, and having in combination two signals at or near one end of the block, controlling train movements in the same direction, one over one track and the other over the other track, mechanisms for operating said signals, electric slots forming parts of the signal operating mechanisms, the circuits of said slots being controlled by the relays of track circuits at the end of the block section, and means operated by the movement of trains over the sub-section and the overlap section for holding the slot circuits open until the train has passed off the overlap section, substantially as set forth.

In testimony whereof I have hereunto set my hand.

JOHN PRESSLEY COLEMAN.
